UNITED STATES PATENT OFFICE.

JOHN H. LINDSAY, OF BROOKLYN, NEW YORK.

AIR-VALVE FOR STEAM-RADIATORS.

SPECIFICATION forming part of Letters Patent No. 499,463, dated June 13, 1893.

Application filed February 6, 1893. Serial No. 461,203. (No model.)

To all whom it may concern:

Be it known that I, JOHN H. LINDSAY, of Brooklyn, in the county of Kings and State of New York, have invented a new and useful 5 Improvement in Air-Valves for Steam-Radiators, of which the following is a specification.

My invention relates to an improvement in air valves for steam radiators in which provision is made for automatically closing the 10 air escape under the influence of heat or the accumulation of water within the valve, and in which the inflow of the steam and outflow of the water of condensation are so established as to prevent interference and the consequent 15 liability of backing up the water in the valve before the air has escaped therefrom sufficiently to establish a circulation of hot steam through the radiator.

A practical embodiment of my invention is 20 represented in the accompanying drawings in which—

Figure 1 is a view of the valve in side elevation. Fig. 2 is a vertical central section of the same, and Fig. 3 is a partial vertical central section of a slightly modified form.

A represents the casing or barrel of the valve secured at its lower end in a seat B having a threaded neck b extending laterally therefrom for the purpose of securing it to a radiator. 30 The seat B is provided with an upper inlet port or conduit b' and a lower outlet port or conduit b², the latter during its course being provided with a bend b³ to form a trap. A pet cock C is connected with the seat B at 35 the base of the trap bend b³ for purposes which will hereinafter more particularly appear. The normal waterline in the trap bend b³ is denoted by a dotted line b⁴. Both the inlet and discharge conduits b' and b² open

40 into the base of an expandible and contractible inner tube or casing D, the walls of which are preferably corrugated, as shown. The tube or casing D rests at its lower end on the bottom of a depression b⁵ in the seat B and at 45 its upper end supports, by means of a flange e, an air tight tubular float E. The float E extends down within the expandible and contractible tube D two-thirds of the length of the tube more or less, and the inlet conduit b' is provided with a nozzle F located underneat the bottom of the float E and having its upper end f closed and openings f'

through its sides for distributing steam laterally into the tube D and preventing it from issuing directly against the bottom of the 55 float. Openings d, d' and d² are arranged at the base, middle and upper portions respectively of the tube D to permit the steam which issues from the nozzle F to circulate within the casing A exterior to the tube D as well as 60 within the said tube D. A head piece G, fixed within the upper end of the casing A, is provided with a centrally located air exit port g adapted to be closed and opened by the stopper H fixed to the upper end of the float 65 E, as the latter is caused to rise and fall.

In the form represented in Fig. 2, I have shown the air discharge conduit g as provided with a downwardly directed flaring mouth g' for receiving the tapered end h of 70 the stopper and I have found it desirable to provide the head G with a downwardly projected annular flange g² to receive the upper end of the tubular float and prevent the displacement of the latter after the parts have 75 been assembled.

Over the top of the casing A and spaced from the head G, I provide a cap I, which may be conveniently screwed onto the top of casing, and is provided with a shoulder K for 80 the purpose of spacing the cap from the air exit conduit g so as to permit the escape of the air from the conduit beneath the cap through suitable perforations in the sides of the cap.

In operation, suppose the water in the trap b³ be on the level of the dotted line b⁴ and steam be turned on to the radiator with which the valve may be connected. Because of the obstruction of the small quantity of water in 90 the trap b³, the air driven by the inrushing steam will rush into the casing A through the port b' and thence through the nozzle F into the expandible and contractible tube D, thence through its walls and upwardly around 95 it and out through the air conduit g and thence through the sides of the cap into the outside air. The water of condensation in the mean time will follow down within the casing A and within the tube D into the exit conduit b² 100 which will continue to discharge it back into the radiator as fast as it rises above the water level of the trap. This action will continue until the tube D has expanded suffi-

ciently to lift the stopper H into engagement with the mouth of the exit conduit g when the further escape of air will be checked and the circulation of steam through the radiator 5 will continue. If for any reason the escape of water from the casing A into the radiator becomes checked, its accumulation within the tube D and casing A will lift the float E and shut off the escape g before the water is blown 10 out to any considerable extent.

When it is desired to rapidly free the radiator from air, the pet cock C may be opened, as shown in Fig. 2, permitting the small 15 quantity of water within the trap b³ to discharge itself and the air to be driven by an inrush of steam through the pet cock as well as through the smaller air escape g at the top. The valve thereby becomes either self-acting or under the control of the occupant of the 20 room at pleasure.

In the form shown in Fig. 3, the stopper H' fixed to the top of the float consists of a flat yielding pad adapted to press against the walls surrounding the lower end of the air 25 escape conduit whenever the float is lifted.

What I claim is—

1. The valve chamber or casing provided with an air discharge port or conduit, an air and steam inlet conduit and a trapped liquid 30 discharge conduit, substantially as set forth.

2. The combination with the valve chamber or casing provided with an expandible and contractible tube therein and an air escape port or conduit, of a float supported

upon the expandible and contractible tube 35 and carrying a stopper for closing and opening the air discharge conduit, an air and steam inlet conduit opening within the expandible and contractible tube beneath the float and a trapped liquid discharge conduit, substantially as set forth.

3. In combination, the valve chamber or casing provided with an air discharge port or conduit and an expandible and contractible tube within the casing, a float supported on 45 the said expandible and contractible tube and carrying a stopper for the air discharge port, separate air and steam inlet and liquid discharge ports and a pet cock connected with the liquid discharge port, substantially as set 50 forth.

4. In combination, the valve chamber or casing provided with an air discharge conduit, a perforated corrugated expandible and contractible tube within the casing, a float 55 supported on said expandible and contractible tube and provided with a stopper for the air discharge, an air and steam inlet entering the casing within the corrugated tube beneath the float, a device for throwing the current of 60 air and steam laterally from under the float and a liquid discharge conduit, substantially as set forth.

JOHN H. LINDSAY.
